UNITED STATES PATENT OFFICE.

HAROLD EDWARD BRIGHT, OF HAMILTON, NEW ZEALAND.

AUTOMATIC OUTFALL FOR THE TIDAL DISCHARGE OF SEWAGE.

Application filed October 10, 1924. Serial No. 742,937.

To all whom it may concern:

Be it known that I, HAROLD EDWARD BRIGHT, citizen of the Dominion of New Zealand, residing at Hamilton, in the Dominion of New Zealand, have invented certain new and useful Improvements in Automatic Outfalls for the Tidal Discharge of Sewage, of which the following is a specification.

10 This invention relates to means employed for controlling the discharge of sewage and the like into tidal waters, where the outgoing or ebb tide is utilized for disposing of said sewage and the like, and provides improvements in the type of sewage discharge control means, wherein the descent of a float which rises and falls with the level of the tidal waters, is utilized to operate the control valve to permit of the discharge of 15 sewage, the same descending movement of the float being further utilized at a later period to bring about the closing of the sewage outlet.

In the aforesaid type of sewage discharge control means, the float was provided with a catch lever, which during the descent of the float engaged a cross head or catch block connected with the control valve and raised the latter.

30 Owing to the fact that the high water levels varied, it was found necessary to arrange the catch lever and the cross head or catch block so that the latter would be engaged by the former, at the lowest high 35 water level, likely to occur, with the result that when a spring tide occurred or whenever the high water level was above said lowest high water level, the earliest portion of the ebb tide was not utilized for the 40 carrying seaward of sewage on account of the control valve not being lifted until the water level receded to that at which the catch lever and crosshead or catch block were arranged to interengage.

45 The main improvement provided by this invention consists in providing on the float a catch lever designed to engage and draw the cross head or catch block with it as soon as the water level commences to fall irrespective of what high water level has been 50 reached, so that the control valve is raised to permit the discharge of sewage at the earliest possible moment after the tide has commenced to run out.

55 The catch lever which is pivoted on the float and weighted to normally assume a ver-

tical position is provided with an upper tooth adapted to engage the cross head or catch block at the lowest high water level likely to occur and with a lower tooth 60 adapted to engage the crosshead or catch block at the greatest high water level while intermediate teeth are provided for engaging said cross head or catch block when the levels of tides are located between the afore- 65 said limits.

Other improvements consist in providing an overflow passage from the chamber in which the control valve operates, should the latter for any reason fail to open, and 70 in the construction and fitting of the various parts to ensure free working of the moving parts.

The invention will be further described in conjunction with the accompanying 75 drawings, wherein:—

Figure 1 is a sectional elevation of the means for operating the sewage discharge gate or valve.

Figure 2 is a side elevation of the apparatus showing the gate or valve chamber in section.

Figure 3 is a plan view of the catch block whereby a connection is made between the tide operated float and the discharge gate or 85 valve, and

Figure 4 is an elevation illustrating the location of the apparatus in relation to a storage tank or reservoir.

The sewage is collected by means of reticulated pipe lines 1 and conveyed to a suitable storage tank or reservoir 2, the discharge of the sewage from the latter being controlled by means of a gate 3, which is opened to permit sewage to be discharged 90 by the descent or falling action of a tide operated float 4, said float being later responsible for the closing of the gate controlling the sewer outlet.

The float is accommodated in a suitable 100 chamber 5 and is capable of vertical movement therein between vertical guides 6. The tide has access to the interior of said float chamber for the purpose of operating the float, through small openings or holes 7 located around the bottom of the chamber, said openings or holes, however, not being of sufficient size to permit of the surge or wave action of the tide being transmitted to the water inside the chamber, so as to ensure 105 that the float 4 therein will rise or fall with a steady movement. The float is adapted to

rise freely in its chamber during the flood of the tide, and in falling during the ebb of the tide, is adapted to engage a catch block 8 and draw the latter downwards.

5 A chain 10 or the like connected at one end to the catch block 8 passes over pulleys 11 and 12 and is secured at its other end to the control gate 3 located in a chamber 13 provided in the discharge pipe line 14 from the 10 storage tank or reservoir 2, said gate 3 being adapted, when the catch block 8 is in its uppermost position, to close the outlet 15 from said chamber 13.

Brackets 16 secured to the top of the float 15 project for some distance above the latter and are provided at their upper ends, which are situated above the water level in the chamber 5 with rollers 17 or the like adapted to work against the guides 6 between which 20 the float 4 operates, said guides 6 being preferably of channel cross section so that the rollers 17 can run therein, while semi-circular projections 18 secured to the sides of the float 4 near the bottom thereof also 25 enter the channel shaped guides 6 and are operable vertically therein. By this means, the length of bearing obtained at the sides of the float 4 in the guides 6 is greater than the diameter of the float 4, thereby ensuring 30 that the said float will rise and fall between the guides 6 without turning or jamming therein.

The catch block 8 is mounted between vertical guides 9 so as to permit it to rise 35 and fall freely between the latter, the following method of attachment being preferred.

Vertical recesses 19 (Figure 3) are provided in the sides of the catch block 8, to 40 pass upon the vertical guides 9 between which the latter operates, while rollers 20 secured in a frame 21 at the rear of the catch block 8 bear against the rear of the said guides 9 to prevent jamming of the catch 45 block should any side strain be exerted thereon when the float 4 is being released from engagement with the said catch block.

As the float 4 falls in the chamber 5 on the ebb of the tide, it engages, by means 50 to be hereinafter described, the catch block 8, and draws the latter down with it, the result of which is that the gate 3 is raised and opens the outlet 15 thereby permitting sewage to escape and to be carried seawards 55 by the outgoing tide.

The float 4 contains a well 22 across which is mounted a horizontal shaft 23^a carrying a centrally pivoted catch lever 23, the upper portion of which is adapted to engage the aforesaid catch block 8.

The catch lever 23 is weighted or has its lower end made heavier than its upper end, so that the latter when the catch lever hangs free or is not in contact with any external 65 agent assumes a vertical position below the

catch block 8. The upper portion of the catch lever 23 contains a series of ratchet like teeth 24 disposed vertically one above the other.

The catch block 8 is hung from the chain 70 10 connecting the same with the control gate 3, in a manner which ensures that it will rise and fall in its guides 9 without twisting or jamming, and is provided with a central lip 26 having a bevelled underside 75 25, said lip 26 being adapted to be engaged and held by any one of the ratchet like teeth 24 on the upper portion of the lever 23, on the float 4 moving downwards in its guides 6 with the receding tide. 80

Assuming that the tide is commencing to rises, the sewage control gate 3 is shut, and the float 4 is resting on the floor of the chamber 5. As the water of the incoming tide enters the chamber 5, the float 4 therein 85 rises until the top of the pivoted catch lever 23 meets the under bevel face 25 of the catch block 8. As the float continues to rise, this bevel face 25 throws back the upper end of the lever 23 until the first or uppermost ratchet tooth 24 thereof passes above the lip 26 of the catch block 8, when the lever 23 under the influence of its weighted lower end, swings back to its normal or vertical 90 position, thereby engaging the said ratchet 95 tooth 24 on the lip 26.

The heights and levels of the various working parts in the float chamber 5 are arranged so that the engagement of the upper ratchet tooth 24 with the lip 26 of the 100 catch block 8 will take place at high water neap tide or at the lowest high water level likely to occur.

The bottom ratchet tooth 24 engaging the lip 26 at high water spring tide, while the intermediate teeth 24 are provided to engage the lip 26 at levels located between the limits mentioned.

The effect of providing the ratchet toothed formation 24 is that the catch block 8 is drawn downwards by the float 4 immediately the latter commences to descend, and irrespective of the height the tide has reached.

On the tide turning and commencing to ebb, the combined weight of the float 4 and catch block 8 being in excess of the weight of the gate 3, the latter is lifted as the float and block descend with the level of water in the float chamber, thereby opening the 120 outlet 15.

An inclined plate or surface 27 formed on or secured to the bottom of the float chamber 5 is so placed that as the float 4 in descending, nears the bottom of the chamber 5, the lower or weighted end of the catch lever 23 comes in contact with the said inclined plate 27, the result of which is that the catch lever 23 is deflected or moved about its axis and withdraws its upper 125 130

toothed portion from engagement with the catch block 8.

Immediately this occurs, the sewage control gate 3 falls by gravity in the chamber 13 and closes the outlet 15 from the latter, at the same time returning the catch block 8 to its raised position ready to be re-engaged by the catch lever 23 when the float 4 rises with the next succeeding flooding of the tide.

The control gate 3 is in the form of a webbed plate, the lower edge 3^a of which is formed to provide a fairly sharp shearing edge, while a pair of arms or wings 30 extend above the upper edge of the gate at the sides thereof, to provide additional bearing surface against the guides 31 between which the said gate operates, in order to prevent turning or jamming of the latter in its guides.

The gate 3 is hung from its upper web, preferably by means of a link or links 32 attached to the lower end of a rod 33 which passes upwards through the top of the gate chamber 13 through a stuffing box 34 therein, the upper end of the said rod 33 being connected to the end of the chain 10 connected with the catch block 8 in the float chamber 5.

The gate 3 is adapted to rise and fall freely in its guides 31 and bears on a slightly battered face in order to ensure that the gate will at all times lie closely against the face containing the outlet 15 and against the facing of its guides 31.

A collar or buffer 35 is formed on or secured to the rod 33, near the top thereof, while a spring 36 passed on the said rod between the collar or buffer 35 and the top of the stuffing box 34, receives the weight of the gate 3 when the latter is lowered or closed, and prevents the said gate from striking the floor of the chamber 13 as it falls in the latter to close the outlet 15.

Should the gate, however, in falling, compress the spring 36 to such an extent that the shearing edge 3^a thereof strikes the floor of the chamber 13, a timber beam or buffer 37 is provided in said floor, to receive the impact of the shearing face 3^a and so prevent the latter from being damaged.

When the gate 3 has been raised to open the outlet 15, and the catch block 8 is disconnected from the float 4, the gate 3 falls with considerable impetus until checked by the spring 36 between the stuffing box 34 and the collar or buffer 35 on the rod 33. The reaction of the spring 36 causes some little vibration which leaves the gate hanging free, yet bearing closely against the facing containing the outlet 15.

The lower or shearing edge 3^a of the gate 3, with the impetus and weight of the falling gate behind it, shears across the outlet 15 and through such sludge, rags, small

sticks or the like as may have lodged therein, larger obstructions having been removed from the sewage by screening the latter before it leaves the storage tank or reservoir 2, to ensure a perfect closure of the outlet 15 by the gate 3.

In order to provide means whereby the action of the float 4 and other parts in the chamber 5 may be observed without interfering with the action thereof, the float chamber is extended to one side, or a separate chamber 29 communicating with the float chamber is provided alongside the latter, such chamber 29 being provided with a manhole 29^a or the like, whereby a person can enter it and observe the action of the various parts contained in the float chamber.

An opening adapted to be normally closed by a suitable plate or cover can be located in the side of the gate chamber 13, and when provided is large enough to permit the removal therethrough of the gate 3, should it be desired at any time to replace or repair the same.

In the event of the gate 3 becoming jammed or blocked and the sewage in the storage tank or reservoir 2 rising above a predetermined safe level, means can be provided to discharge said sewage through the gate chamber 13 independently of the gate 3.

Accordingly, an outlet or overflow 38 is provided from the chamber 13 near its upper end and in the same horizontal plane as the highest level which it is desired that sewage should attain in the tank or reservoir 2. This outlet 38 is connected by means of a pipe 39 to the pipe 40 which normally carries the sewage from the discharge outlet 15 into tidal water.

On the sewage reaching its highest safe level in the storage tank 2, the former will rise to a corresponding level in the chamber 13 and overflow through the outlet 38 and pipe 39 into the pipe 40 from whence it will be discharged seawards.

When the storage tank or reservoir 2 is located at a higher level than the top of the gate chamber 13, the overflow pipe 38 from the latter is not provided, and the top of the said chamber 13 is completely closed to prevent any leakage of sewage therethrough. In this case an overflow pipe can be provided from the storage tank or reservoir 2.

What I do claim and desire to obtain by Letters Patent of the United States of America is:—

1. In apparatus wherein a sewage control gate is operated to open an outlet by means of a descending float, a ratchet-toothed catch lever pivotally mounted on the float, a catch block connected with the gate and arranged to be engaged by the ratchet-toothed catch lever whereby the control gate begins to

open as soon as the float commences to descend, substantially as described and illustrated.

2. In apparatus wherein a sewage control gate is operated to open an outlet by means of a descending float, a ratchet-toothed catch lever pivotally mounted on the float, a catch block connected with the gate and arranged to be engaged by the ratchet-toothed catch lever whereby the control gate begins to open as soon as the float commences to descend, the catch lever having a series of teeth extending from an upper tooth, adapted to engage the catch block at a high water neap tide, to a lower tooth, adapted to engage the catch block at a high water spring tide, substantially as described and illustrated.

3. In apparatus wherein a sewage control gate is operated to open an outlet by means of a descending float, a ratchet-toothed catch lever pivotally mounted on the float, a catch block connected with the gate and arranged to be engaged by the ratchet-toothed catch lever whereby the control gate begins to open as soon as the float commences to

descend, brackets on the float, rollers carried by the brackets above the water level, projections on the float, and vertical guides for receiving and guiding the rollers and projections, substantially as described and illustrated.

4. In apparatus wherein a sewage control gate is operated to open an outlet by means of a descending float, a ratchet-toothed catch lever pivotally mounted on the float, a catch block connected with the gate and arranged to be engaged by the ratchet-toothed catch lever whereby the control gate begins to open as soon as the float commences to descend, guide rails, the catch block being recessed to pass between the guide rails, rollers carried by the block and operable against the rails, a lip on the block having a bevelled under surface, the lip being engageable by the ratchet-toothed catch lever, substantially as described and illustrated.

Signed at Hamilton in the Provincial District of Auckland, in the Dominion of New Zealand, this 27th day of August, 1924.

HAROLD EDWARD BRIGHT.
